CLAIM

The ornamental design for a camera extension pole, as shown and described.

DESCRIPTION

FIG. 1 illustrates a front perspective view of a camera extension pole showing the new design.

FIG. 2 illustrates a left orthogonal view thereof;

FIG. 3 illustrates a right orthogonal view thereof;

FIG. 4 illustrates a rear orthogonal view thereof;

FIG. 5 illustrates an enlarged perspective view of a bottom section thereof;

FIG. 6 illustrates a top elevational view thereof;

FIG. 7 illustrates a bottom elevational view thereof; and,

FIG. 8 illustrates a right perspective view thereof.

The broken lines showing are included for the purpose of illustrating the environment of the design only and form no part of the claimed design.

1 Claim, 8 Drawing Sheets(56)
